(57) CLAIM

The ornamental design for a fingernail protector, as shown and described.

DESCRIPTION

FIG. 1 is a front side elevation view of the closed fingernail protector showing my design;

FIG. 2 is a rear side elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front side elevation view of the open fingernail protector;

FIG. 8 is a rear side elevation view thereof;

FIG. 9 is a left side elevation view thereof;

FIG. 10 is a right side elevation view thereof;

FIG. 11 is a top plan view thereof;

FIG. 12 is a bottom plan view thereof;

FIG. 13 is a reference drawing that shows the fingernail protector in use; and,

FIG. 14 is another reference drawing that shows the fingernail protector in use.

Broken lines indicate environment and are not part of the invention.
